UNITED STATES PATENT OFFICE.

ALEXANDER ARMSTRONG, OF MOUNDSVILLE, WEST VIRGINIA, ASSIGNOR OF ONE-HALF TO WILLIAM F. WEAVER, OF SAME PLACE.

COMPUTING-SCALE BEAM.

SPECIFICATION forming part of Letters Patent No. 596,391, dated December 28, 1897.

Application filed May 28, 1897. Serial No. 638,564. (No model.)

To all whom it may concern:

Be it known that I, ALEXANDER ARMSTRONG, a citizen of the United States, residing at Moundsville, in the county of Marshall 5 and State of West Virginia, have invented certain new and useful Improvements in Computing-Scale Beams; and I do declare the following to be a full, clear, and exact description of the invention, such as will enable others skilled in the art to which it appertains to make and use the same.

My invention relates to improvements in computing scale-beams; and the object is to provide a simple, effective, and reliable device of this character for expeditiously ascertaining the weight and price of a given commodity.

To these ends the novelty consists in the construction, combination, and arrangement 20 of parts, as will be hereinafter more fully described, and particularly pointed out in the claim.

In the accompanying drawings the same reference-characters indicate the same parts 25 of the invention.

Figure 1 is a front elevation of my improved computing scale-beam. Fig. 2 is a top plan view. Fig. 3 is a front end view of the same, and Fig. 4 is a transverse section of the same. 30 1 represents a scale-beam comprising the parallel horizontal arms 2 and 3, connected at their inner ends by a vertical bar 4 and at their outer ends by the corresponding bar 5, terminating in the usual curved arm 6. The 35 arm 2 is provided with the usual index, divided off into pounds and ounces, which the poise 7 traverses. The lower arm 3 is divided into pounds only, and 8 represents the poise traversing said pound-scale.

40 9 represents a cylindrical barrel journaled in a rectangular horizontal frame 10 on a longitudinal parallel shaft 11, the outer end of which is provided with a pointer 12.

45 13 represents a thumb-button fixed to the pointer 12, and 14 represents a scale-dial fixed on the end of the frame 10, and it is provided with arbitrarily arranged figures represent-

ing the price per pound of an ordinary article in daily use.

The barrel 9 is longitudinally divided into 50 parallel sections arranged in pairs, the upper line of each pair representing the computed price of an article per ounce and the lower line the computed price per pound.

Assuming that the article to be sold retails 55 at five cents per pound, the pointer 12 is moved to the figure "5" on the dial 14. This rotates the barrel and brings the corresponding section in line with the finger 7 of the poise 7, representing the ounces, and the finger 8' 60 of the poise 8 will be in line with the pounds in the same section. If the article weighs five pounds, the poise is moved along the scale until it balances, when it will be found that its finger points to "25" on the barrel, 65 which is the computed price of five pounds of any article at five cents per pound. If the weight of an article is to be determined in ounces, then the poise 7 is used, and when it is balanced its finger will indicate the price 70 of a given number of ounces.

The outer end of the barrel is provided with three or more annular series of figures, the first of which contains the computed prices up to fifty pounds, the second to one 75 hundred pounds, and the third to one hundred and fifty pounds, and are used when the corresponding loose weights 15 15 are used, each of which represents fifty pounds.

Although I have specifically described the 80 construction and relative arrangement of the several elements of my invention, I do not desire to be confined to the same, as such changes or modifications may be made as clearly fall within the scope of my invention 85 without departing from the spirit thereof.

Having thus fully described my invention, what I claim as new and useful, and desire to secure by Letters Patent of the United States, is—

90 A scale comprising a rotating computing-barrel 9, substantially as shown and described, and mounted on the shaft 11, a pointer 12 fixed on said shaft so as to rotate simultane-

ously with said barrel, a scale-dial 14 fixed intermediate said pointer and the contiguous end of said barrel, a duplex scale-beam 1 comprising the horizontal arms 2 and 3, the former divided off to represent ounces and the latter to represent pounds, the poise 7 adjustably mounted on the arm 2 and provided with the finger 7' and the poise 8 similarly mounted on the arm 3 and provided with the finger 8',

said fingers 7' and 8' being arranged to independently traverse said barrel, as and for the purpose set forth.

In testimony whereof I hereunto affix my signature in presence of two witnesses.

ALEXANDER ARMSTRONG.

Witnesses:

K. R. MARTIN,
C. A. WEAVER.
